UNITED STATES PATENT OFFICE.

HENRY WARREN ALEXANDER, JR., OF PHILADELPHIA, PENNSYLVANIA.

DESIGN FOR A CANDY MINT.

Application filed May 13, 1922. Serial No. 2,217. Term of patent 3½ years.

To all whom it may concern:

Be it known that I, HENRY WARREN ALEXANDER, Jr., a citizen of the United States, residing at Philadelphia, in the county of Philadelphia and State of Pennsylvania, have invented a new, original, and ornamental Design for Candy Mints, of which the following is a specification, reference being had to the accompanying drawing, forming a part thereof.

The figure is a face view of a candy mint, showing my new design.

I claim:

The ornamental design for a candy mint, as shown.
